[57] CLAIM

The ornamental design for a faucet set, as shown and described.

DESCRIPTION

FIG. 1 is a perspective view of a faucet set showing my new design;

FIG. 2 is a front elevational view of one handle thereof, the rear and side being the same as the front shown;

FIG. 3 is a top plan view of FIG. 2;

FIG. 4 is a front elevational view of a modified form of the handle shown in FIG. 2, the right side being the same as the front shown;

FIG. 5 is a top plan view of FIG. 4;

FIG. 6 is a left side elevational view of FIG. 4;

FIG. 7 is a rear elevational view of FIG. 4;

FIG. 8 is a left side elevational view of the spout thereof, the right side being a mirror image of the left side shown;

FIG. 9 is a top plan view of FIG. 8;

FIG. 10 is a front elevational view of FIG. 8;

FIG. 11 is a rear elevational view of FIG. 8;

FIG. 12 is a bottom plan view of FIG. 8;

FIG. 13 is a left side elevational view of a modified form of the spout shown in FIG. 8, the right side being a mirror image of the left side shown;

FIG. 14 is a top plan view of FIG. 13;

FIG. 15 is a front elevational view of FIG. 13; and

FIG. 16 is a rear elevational view of FIG. 13.

The broken line representation of a portion of a sink in FIG. 1 is for purposes of illustration only.
